DALLAS D. PARSHALL, OF WATERVLIET, NEW YORK, ASSIGNOR TO THE JACK FROST COMPANY, OF STAMFORD, CONNECTICUT, A CORPORATION OF DELAWARE.

THERMOSTATIC-CONTROL MECHANISM FOR DOMESTIC REFRIGERATING SYSTEMS.

Application filed May 11, 1925. Serial No. 29,271.

The general object of my present invention is to provide an improved form of control mechanism automatically responsive to temperature, suitable for use in controlling the circulating motor of a mechanical refrigeration system, and primarily devised, and especially adapted for use in domestic refrigerating systems. More specifically, the object of my invention is to provide a thermostatically actuated motor control switch characterized by its simplicity, strength, ruggedness and by its effectiveness for its intended purposes.

The various features of novelty which characterize my invention are pointed out with particularity in the claims annexed to and forming a part of this specification; but for a better understanding of the invention, however, its advantages and specific objects attained with its use, reference should be had to the accompanying drawings and descriptive matter in which I have illustrated and described the best forms of my invention.

Of the drawings:

25 Fig. 1 is a diagrammatic elevation of a refrigeration system in which my invention is incorporated;

Fig. 2 is a vertical section through the thermostatic control switch;

30 Fig. 3 is a section on the line 3—3 of Fig. 2; and

Fig. 4 is a section on the line 4—4 of Fig. 3.

In the drawings, I have illustrated the use of my invention in a refrigerating system comprising a cooling reservoir or expansion chamber A adapted for insertion in an ice box or refrigerator for domestic use, receiving a liquid heat absorbing fluid or refrigerant from a condenser B through a pipe C containing a pressure reducing valve D. A circulating pump E withdraws the vaporized cooling fluid from the cooling reservoir A through a conduit F and after compressing the vapor discharges it into the air cooled condenser B.

My present invention is concerned with the construction and arrangement of means for automatically controlling the operation 50 of the motor G which is operatively connected to the circulating pump E, in response to temperature requirements, and comprises the thermostatic switch mechanism shown in Figs. 2, 3, and 4 of the drawing. This mechanism includes a thermo-

stat which in the preferred construction illustrated comprises a cast metal cup-shaped member H.

As shown, the member H rests on top of the expansion chamber A between centering lugs A' on the top wall of the latter and is secured in place by set screws A³ passing through the lugs.

The upper end of the chamber space H' in the member H is closed by a cylindrical bellows element J which partially fills the space H' and has a closed lower end J' and an out-turned flange J² at its upper end. The flange J² is clamped between the rim or upper edge H² of the member H, and a clamping plate or head K secured to the member H by screws or bolts K'. L represents a gasket provided to insure a tight joint. An opening H³ formed in the bottom wall of the chamber space H' and normally closed by a screw plug H⁴, is provided for charging the space H' with a suitable volatile fluid such as SO₂.

The head K is formed with a downwardly extending cylindrical boss K² forming a tubular guide for stem J³ secured at its lower end to the lower end J' of the bellows element J. The stem J³ which extends above the head K is connected above the latter to a control switch M in such manner that when the SO₂ in the space H' expands on an increase in temperature, and collapses the bellows J and thereby moves the stem J³ upwardly, the switch M closes a motor energizing circuit and starts the motor G into operation. When the resultant expansion of the refrigerant in the chamber A effects a sufficient lowering of the temperature of the SO₂ in the chamber H', the consequent expansion of the bellows element J actuates the switch M to open the previously closed motor circuit, thereby stopping the motor G and the circulation of the refrigerant. The expansion of the bellows element J when the vapor pressure in the chamber H' is reduced is due in part to atmospheric pressure on the upper side of the element, and in part of the action of a helical spring O. The latter surrounds the tubular guide K² with its lower end abutting the closed end J' of the bellows element J, and with its upper end abutting a nut P threaded on the guide K². By adjusting the nut P on the threaded guide K² it is thus possible to regulate the tension of the

spring O so as to require a greater or lesser pressure of the SO₂ in order to collapse the bellows element J. As shown the nut P is formed with notches in its periphery to 5 facilitate its rotation by suitable implement inserted through a slot K³ in the head K.

The motor controlling switch M comprises a mercury containing tube clamped in a support Q which comprises a horizontal shaft 10 portion Q' journaled in a boss K⁴ formed on the upper side of the head K. The rise and fall of the stem J³ rotates the shaft Q' by connections which include a lever R pivoted intermediate its ends to the stem J³ by 15 a pin J⁴ which passes through the walls of a slot formed in the upper end of stem J³ and through which the lever R extends. The lever R has one end pivotally connected to the head K by means of a pair of pins K⁵ 20 and K⁶ anchored in the side walls of a slot formed in an integral upstanding lug K' on the head K. One end of the lever R extends into the last mentioned slot with its upper edge engaged by the pin K⁵ and its 25 lower edge engaged by the pin K⁶. The opposite end of the lever R extends between upper and lower pins or projections Q² and Q³ carried by the member Q and extending transversely to the shaft Q'.

30 The switch M and the connections through which it is operated by the bellows stem J³ are enclosed by a casing formed in part by the head K, in part by a bracket like extension H^c of the body H, and in part by a 35 cover S detachably connected to the head K.

The mercury containing tube of the switch M is provided with two contacts M' and M² carried by conductors extending through the wall of the tube. The contacts M' and M² 40 are so disposed as to be electrically connected by the mercury in the tube when the bellows J is compressed and the tube is thereby tilted into the position shown in Fig. 3. When the bellows J is expanded the tube tilts into a 45 position in which the mercury no longer connects the contacts M' and M². When the contacts M' and M² are connected by the mercury in the switch tube, the motor G is energized from line conductors 1 and 2 50 through circuit connections including a conductor 3 running from line conductor 2 to one terminal of the motor, a conductor 4 running from the line conductor 1 to the contact M', and a conductor 5 running from the contact M² to the second terminal of the 55 motor G.

The thermostatic control mechanism disclosed is simple, effective, durable, and practically fool-proof as is desirable for its intended use in domestic refrigeration systems. 60 The manner in which the lever is pivotally connected to the stem J³ and to the head K tends to prevent objectionable lateral play of the lever R while at the same time permitting 65 of a certain amount of lost motion

which contributes to a quick and positive make and break of the mercury connection between the contacts M' and M². The switch tube proper forms a relatively inexpensive, durable, and reliable form of switch which 70 can easily be replaced when replacement is necessary. The thick walls of the thermostat casing H tend to an efficient and accurate control of the refrigerator temperature, by permitting the thermostatic element to 75 respond to gradual changes in the refrigerator temperature, while protecting the thermostatic element against the immediate effect of sudden and momentary changes in the refrigerator temperature such as are 80 caused by the occasional and temporary opening of the door of the refrigerator in which my improvement is incorporated. The thick walls of the thermostatic casing H and the cover S form a strong and rugged 85 housing for the more delicate operating parts of the thermostatic mechanism which is especially desirable for domestic service with unskilled attendance because it minimizes the danger of accidental breakage of, 90 or injury to the mechanism.

I claim:—

1. A thermostatic regulator comprising in combination a casing having a removable part, a flexible thermostatic element mounted in said casing, a switch actuator connected to said element and extending through said removable casing part, and a lever mounted on said removable casing part and engaged by said actuator, a rocking element 100 journaled on said casing part and connected to said lever to be oscillated by said actuator and a switch tube mounted on said rocking element, internal contacts carried by said tube, and a body of mercury connecting said contacts in one position but not in another of the positions into which the tube is turned by the oscillation of said lever.

2. A thermostatic regulator comprising a 110 cup-shaped casing, a casing head secured to the casing body and formed at its underside with an externally threaded hollow boss, a cup-shaped bellows element mounted in said casing and comprising an out-turned flange 115 at its upper end clamped between the casing and head and uniting with the casing body to form an expandable collapsible chamber space for a volatile thermostatic element, a switch actuator slidably received 120 in said boss and secured at its lower end to said bellows, a nut threaded on said boss, a spring compressed between said nut and the bottom wall of said bellows, said head being slotted to permit adjustment of said nut, and a switch mechanism mounted on said head and connected to and operated by said switch actuator.

3. A thermostatic regulator comprising a 130 cup-shaped casing, a removable head for

closing the upper end of said casing, a cup-shaped bellows element located within said casing and having an out-turned flange at its upper end clamped between said head and casing whereby a chamber for a volatile thermostatic agent is provided between said casing and said bellows element, an axially movable switch actuator extending through said head with its lower head in engagement 5 with the bottom wall of said element, and a switch mechanism mounted on said head and comprising a lever having a fulcrum connection with said head and engaged and oscillated by said actuator, a rocking element journalled on said head to turn about an axis generally parallel to said lever and connected to the latter to be oscillated as the lever is oscillated, a sealed tube carried 10 by said rocking element and partially filled 15 with mercury, and contacts mounted in said tube to be connected in one but not in another of the positions into which said rocking element is oscillated.

20 4. A thermostatic regulator comprising 25 in combination a cup-shaped casing, a head

detachably secured thereto, a flexible member mounted in said casing and uniting with the latter to provide a volatile fluid containing chamber of which said member forms an expandible wall, an actuator slidably 30 mounted in said head and extending through the latter and connected at its inner end to said flexible member, a lever having a fulcrum connection to said head and pivotally connected to said actuator, a switch tube 35 support pivotally mounted on said head, and comprising parts engaging said lever whereby by the reciprocating movements of said actuator oscillates said tube support, a tube 40 mounted on said support, contacts supported within said tube and a body of mercury therein connecting said tube in one position but not in another of the positions into which it is turned by the oscillations of said lever.

45 Signed at Albany, in the county of Albany and State of New York, this 22nd day of April, A. D. 1925.

DALLAS D. PARSHALL.
